UNITED STATES PATENT OFFICE.

CHARLES W. HOLTZ, OF NEW YORK, N. Y.

PICTURE-HOOK HANGER.

No. 907,599.

Specification of Letters Patent.

Patented Dec. 22, 1908.

Application filed May 25, 1908. Serial No. 434,808.

To all whom it may concern:

Be it known that I, CHARLES W. HOLTZ, a citizen of the United States, residing at New York city, in the borough of Manhattan, county and State of New York, have invented certain new and useful Improvements in Picture-Hook Hangers, of which the following is a clear, full, and exact description.

10 This invention is to provide a simple and improved form of picture hook hanger.

The object of the invention is to provide a device of this character with a pocket or recess, which will retain the hook without 15 the aid of any strain upon the wire.

In carrying out the invention I provide a pocket or recess which will support at least half of the hook in stable equilibrium, and I provide independent grooves for the wire so 20 positioned that when the hook is to embrace the picture molding and the holder is withdrawn, the wire end of the hook will come in contact with the wire held in the groove, and hold the same suspended during 25 the continued withdrawal of the picture hook hanger.

The scope of my invention will be pointed out in the claims.

In the accompanying drawings, Figure 1 30 is a front elevation of my improved device, showing a hook in position. Fig. 2 is a section on line 2—2 Fig. 1. Fig. 3 is a side elevation of the device with the hook removed.

Preferably I form the picture hook hanger 35 as a head 1 provided with a socket 2 having resilient means therein which may grasp a stick or end of a broom or other device to make practically a continuation of the same, although it will be obvious that this detachable feature need not be present in my invention.

The head 1 is provided with two outstanding arms or wings 4 and 5, each wing or arm having a groove 6 across its top and parallel 45 with the face of the hanger. In the mid portion of the head and open to the top I form a supporting wall 8 at the back of the same, of at least half the height of the picture hook to be grasped. I prefer to form a 50 short wall 9 in the forward part of the recess 7, but I do not limit myself to any particular

height for this front wall. I prefer to form it short so that the hook will have no impediment to withdrawal from the recess when it is desired to do so. The wall 8 is 55 made that height specified so that the hook will be stably supported within the same, its greatest weight resting on the bottom of the recess 7.

In operation a hook 10 is placed, wire end 60 down, within the recess 7 in the position shown in Fig. 2. The wire of the picture, which is attached to the picture at this time is passed across the grooves in the right and left arms of the head 1, bridging the gap 65 above the hook where it crosses the recess 7. The frame, wire and hook hanger are then elevated into position at the end of a pole as before described by preference, and the large end of the picture hook 10 caused to embrace 70 a picture molding. The head 1 is then lowered and as the hook is caught by its upper end on the molding it will be withdrawn from its socket or recess 7, during which withdrawal the wire end of the hook will 75 come into contact with the wire lying across the recess, and in the grooves as aforesaid, engage the same, and prevent the withdrawal of the wire upon the continued withdrawal of the head. 80

It will be obvious that the device described is just as applicable for the taking down of pictures as it is for the hanging of the same.

I claim as my invention:

1. The herein described picture hook hanger comprising a head having a deep recess with a comparatively high wall and a comparatively low wall on the opposite side forming a pocket at the base of the recess 90 adapted to receive the wire end of a picture hook, grooves for the picture wire in the head a substantial distance above said pocket, whereby the wire will be free of the hook when both are in position. 95

2. The herein described picture hook hanger comprising a head having right and left arms or wings grooved across their tops parallel with the face of the head for the picture wire, a recess between the right and left wings or arms, said recess having a comparatively high rear retaining wall, and a 100

comparatively low forward retaining wall forming a pocket between the two walls within the recess at a substantial distance below the aforesaid grooves, whereby the
5 wire and the hook will be free of each other until the pole is withdrawn, and the wire then brought into contact with the hook.

Signed at New York city, New York this
21st day of May 1908.

CHARLES W. HOLTZ.
